LUTHER L. KENNEDY, OF BROOKLYN, NEW YORK, ASSIGNOR TO MERGEN-
THALER LINOTYPE COMPANY, A CORPORATION OF NEW YORK.

LINOTYPE-MACHINE.

No. 796,844.

Specification of Letters Patent.

Patented Aug. 8, 1905.

Application filed March 10, 1905. Serial No. 249,374.

To all whom it may concern:

Be it known that I, LUTHER L. KENNEDY, of Brooklyn, county of Kings, and State of New York, have invented a new and useful Improvement in Linotype-Machines, of which the following is a specification.

This invention has reference to the distributor-driving connections of linotype-machines in which two magazines, one overlying the other, are employed, as represented in United States Letters Patent No. 640,033 to J. R. Rogers and in the pending application of J. R. Rogers, Serial No. 252,002. In these machines there is a distributing mechanism for the upper magazine and a second distributing mechanism for the lower magazine. Between each distributor and the underlying magazine there is a channeled throat or entrance for guiding the released matrices to their appropriate channels in the magazine. These channeled throats are hinged at their lower sides in order that they may be turned backward to give access to the distributor and to the upper end of the magazine. When they are thus opened, so that they no longer guide the descending matrices, it is important that the distributor shall be stopped. For this purpose it has long been customary in machines with one magazine to drive the distributor through a clutch with a throw-out device controlled by the hinged throat, so that when the latter is open the clutch is disconnected and the distributor stopped and permitted to remain at rest until the operator throws the parts into engagement by hand.

In the present form of machine the lower distributor receives motion from the upper, and consequently the opening and closing of the upper throat will stop and start both distributors. In this machine it is necessary to prevent the starting of the distributors by the closing of either throat when the other is open. My invention has in view an arrangement of devices for this purpose.

Referring to the drawings, Figure 1 is a perspective view of one end of the two distributors and their driving connections all in operative or running position. Fig. 2 is a similar view illustrating the manner in which the movement of the lower-distributor throat locks the parts to prevent the starting of the distributor by the opening and closing of the upper throat. Fig. 3 is a vertical cross-section on the line 3-3, Fig. 1. Fig. 4 is a dia-

gram illustrating the arrangement of the distributor-driving connections.

The distributing mechanisms are of the form usually used in linotype-machines consisting of a horizontal bar provided in the lower edge with permuted teeth to suspend the toothed matrices and adjacent screws to engage the matrices and carry them along the bar until they arrive over the corresponding channels in the magazine, as described, for example, in Letters Patent of the United States No. 436,531.

Referring to the drawings, A represents the upper-distributor bar, B one of the adjacent screws for feeding the matrices along the bar, and C the hinged channeled throat or entrance through which the matrices falling from the distributor pass into the upper magazine D, as usual.

A', B', and C' represent the corresponding parts for delivering matrices to the lower magazine D'.

The upper-magazine screws are connected, as usual, by pinions b b' and receive motion through driving-belt F, pulley G, and friction-clutch H. The pulley and its cooperating clutch are mounted on an extension of one of the screws, and the clutch is pressed axially into engagement with the pulley by a spiral spring h. The disengagement is effected by means of a rocking throw-out lever I, one end of which carries a stud to engage the collar h' with inclined surfaces on one side. When the end of the arm is thrown upward, it is acted upon by the inclined surfaces of the collar, which is forced axially to the left, thereby throwing the clutch out of action and permitting the upper distributor to stop.

The lower-distributor screws are driven from the upper distributor in the manner shown in Fig. 4, the hub of the clutch H being provided with a pulley h², from which a belt h³ is extended to an idle pulley h⁴, from which a second belt h⁵ is extended downward to a pulley on one of the lower-distributor screws B'. It follows, therefore, that when the driving-clutch H is disengaged the lower-distributor screws, as well as the upper, are stopped.

The clutch-controlling arm I is mounted on a horizontal shaft i in the main frame and urged upward by a spring j, Fig. 3. The central portion of the arm is of tubular form and is extended to the right and provided with

a horizontal slide i' , urged to the left by a spring i^2 . The inner end of the slide i' has a lip or shoulder which rests normally against the sliding bar i^3 , mounted in the channel entrance or throat C, as shown in Fig. 1. As the throat is held in its operative position the end of the bar i^3 presses forward on the slide i' and holds the rocking finger I downward out of the path of the clutch. The bar i^3 is connected, as usual, with the laterally-yielding partitions or division-plates in the throat C, so that when a matrix lodges in an improper position it will be crowded laterally and cause the partitions to move the bar i^3 , which being notched in the front will permit the end of the slide i' to fall backward into the notch, thereby allowing the finger I to rock upward and trip the clutch out of action.

The action of the bar i^3 in releasing the arm I is essentially the same as in the ordinary linotype-machine.

In order that the lodgment of matrices in the lower magazine may in like manner stop the action of the parts, it is provided as usual with a sliding bar i^6 , connected to the partitions or division-plates, and this bar is arranged to act on the lower end of a lever K, pivoted to the main frame and arranged to act at its upper end against the slide i' . When the bar i^6 is pushed to the left, it moves the lever K, the upper end of which in turn pushes the slide i' to the right until its shoulder or finger is in position to enter the bar i^3 , the effect being to allow the slide i' to fall back and permit the finger I to disengage the clutch.

In the operation of the machine it is occasionally necessary to open the throat-plate C' of the lower magazine. When this occurs, it is necessary that the distributers shall both be stopped, as otherwise the delivery of matrices to the lower distributer would continue. For this purpose the lower end of the lever K is beveled, as shown in Fig. 1, so that when the lower throat C' is swung backward or opened, as shown in Fig. 2, the bar i^6 will act on the end of the lever K and move the same, causing it in turn to move the upper slide i' to the right in order to cause the disconnection of the clutch by arm I, as before explained. When the clutch is thus disengaged by the opening of the lower-throat plate, it is important that it shall be locked out of action, so that it cannot be started by the opening or closing of the upper throat C while the lower throat C' is open. For this purpose I provide, as shown in Figs. 1, 2, and 3, a dog or latch L, mounted on a horizontal pivot l , its forward end being weighted. Its rear end is so formed and located that when the machine is in action it rests beneath the end of the slide i' , as shown in Figs. 1 and 3, and is operative. When, however, the slide i' is moved to the right to release the arm I and to cause the disengagement of the clutch, the

end of the dog L rises alongside of the end of the slide i' , as shown in Fig. 2, thus locking the slide in its abnormal position, so that it cannot be acted upon by the bar i^3 . In consequence of this the throat C may be opened and closed again without causing the clutch to be tripped into action. When both throats C and C' are closed, the distributer is started by hand by throwing the arm I downward from the position shown in Fig. 2 to the position shown in Figs. 1 and 3 out of engagement with the clutch.

My invention resides chiefly in the latch L or equivalent means for keeping the clutch out of engagement until the lower throat C' is closed to its operative position.

I believe myself to be the first to combine with two distributing mechanisms driven in unison means whereby the driving mechanism is held out of action until the parts of both distributers are adjusted in operative positions, and it is manifest that the latch L may be replaced by any other equivalent device or devices for the purpose.

The operation of the parts is as follows: When the machine is in action, the parts are in the positions shown in Fig. 1, the clutch-controlling arm I being held out of action by the pressure of bar i^3 against the end of the slide i' , seated in the upturned end of arm I. If a matrix lodges in the upper throat C, the bar i^3 is urged to the left, so that its notched end disengages from the slide i' , thereby allowing the tripping-arm I to engage the collar and arrest the motion of both distributers. If, on the other hand, a matrix lodges in the lower throat, the bar i^6 will be urged to the left, thereby actuating the lever K, which will push the slide i' to the right, thereby disengaging it from the retaining-bar i^3 , so that the clutch-tripping arm may rise into action, as before, and stop the action of both distributers. If the upper throat C is opened to gain access to the upper distributer, the bar i^3 will be carried rearward away from the slide i' and the clutch-tripping arm permitted to act. At the same time the latch L will rise and lock the slide to the right in inoperative position, so that when the throat C is closed it will fail to start the distributer. If the lower throat C' is opened to gain access to the lower distributer, its bar i^6 and actuating-lever K will cause the slide i' to move to the right, thereby permitting the clutch-tripping arm I to act, the dog L at the same time locking the slide i' , so that the clutch cannot be started automatically. It will be observed that the arrangement described holds the entire distributing mechanism out of action whenever the throat of either magazine is open.

When the distributer is to be started again, the clutch-controlling arm I is thrown out of action by hand and is automatically locked out by the parts before described.

Having described my invention, what I claim is—

1. The two distributers, the receiving-throats thereunder, in combination with a clutch and connections therefrom for driving both distributers, means connected with the lower throat for disengaging the clutch, and means for automatically locking the clutch out of action when disengaged.

2. The combination of two distributers, movable throats thereunder, a clutch and driving connections thence to the distributers, means for disengaging the clutch by the movement of the upper throat, means for disengaging the clutch by the movement of the

lower throat, and means for locking the clutch out of action when disengaged by the action of the lower throat.

3. In a linotype-machine, the combination of a distributer-driving clutch, a trip device to throw the same out of action, and two distinct means for throwing the trip device into action.

In testimony whereof I hereunto set my hand, this 28th day of February, 1905, in the presence of two attesting witnesses,

LUTHER L. KENNEDY.
